UNITED STATES PATENT OFFICE

CLARENCE C. SHIPP, OF INDIANAPOLIS, INDIANA

RADIATOR-BOX DAMPER

Application filed April 24, 1929. Serial No. 357,855.

This invention relates to means for introducing air from outside of a building to within the building across a heating radiator. In the heretofore commonly used structures for this purpose, a passageway has been provided through the wall of the building back of a heating radiator and a single damper was positioned in the passageway to swing away from the radiator outwardly to an open position so that the opening of the damper had to be made against the inflowing air.

In school rooms, auditoriums, and the like, where it is imperative to provide ventilation by changing the air within the rooms, a partial vacuum is actually maintained in the rooms when the air is to be changed by flues or fans designed to withdraw the air from the rooms. Therefore, it is to be seen that with the employment of the damper heretofore used as above described, there is considerable pressure exerted against the damper tending to swing it inwardly due to the air tending to flow therewith to replace that in the room which has been withdrawn. Along with this problem of the incoming air tending to force the damper closed was to be considered the fact that the thermostat commonly used to open the damper operated only to pull the damper open upon a certain room temperature being reached so that, such as in the morning, when the air withdrawal device was first set in operation, no fresh air could pass the damper until after the room reached the temperature at which the thermostat would normally tend to start pulling the damper open. The result was that the air was not changed in the room as frequently as was necessary.

My invention overcomes the difficulties as above described, and has among its principal objects, the automatic opening of dampers to permit an inflow of fresh air irrespective of a thermostat immediately upon creation of a slight vacuum within the room being ventilated; and a further opening of the dampers upon a predetermined increase in room temperature. Other important objects are the provision of a structure that tends to serve as a baffle in retarding sudden gusts of wind from passing the damper into the room; that

is removably secured from the inside of the building to permit easy replacement of, or work on the dampers; and that has shielded damper hinges protected from moisture and dust and that will not corrode.

These and other objects will be apparent in the following description of one particular form of my invention made in reference to the accompanying drawings, in which—

Fig. 1, is a front elevation of a heating radiator with my invention applied thereto;

Fig. 2, a vertical section on an enlarged scale on the line 2—2 in Fig. 1;

Fig. 3, a vertical elevation on the line 3—3 in Fig. 1;

Fig. 4, a vertical elevation on the line 4—4 in Fig. 2;

Fig. 5, a horizontal section through the end of the radiator housing on the line 5—5 in Fig. 3;

Fig. 6, a fragmentary front perspective view of the damper box and lower radiator housing;

Fig. 7, a horizontal section on the line 7—7 in Fig. 2; and

Fig. 8, a detail in bottom plan view of the lower radiator box housing door fastening means.

Like characters of reference indicate like parts throughout the several views in the drawings.

In erecting the wall 10 of the building in which the invention is to be applied, a wall box 11 is properly positioned in the wall with the baffles 12 across its outer opening to prevent entrance of rain, sleet and snow, and a screen 13 to prevent entrance of foreign matter, all as has been commonly employed heretofore, the particular details of the box not forming a part of the invention herein described. A box extension 14 is provided to telescope over the box 11 so as to provide a box structure extensible for varying widths of walls.

From the inside of the wall 10 is imbeded therein the rectangular wooden frame 15, having the mortar cleats 16 secured therearound to securely retain the frame in place. Against the inner face of the frame 15 is positioned and attached thereto by the screws 17

the flange 18 of the rear section 19 of the radiator housing base generally designated by the numeral 20. The section 19 is rectangular in cross-section in planes parallel to the flange 18 and projects forwardly from the flange a short distance.

A damper box 21 is entered from the rear of the section 19 and secured thereto preferably by welding. The damper box 21 is thus made a part of the section 19 and projects rearwardly from the flange 18 through the frame 15 and slidably into the extension 14, the damper box 21 therefore being removable from the wall 10 upon removal of the section 19.

Within the damper box 21, Fig. 2, is a centrally located floor 22 parallel to the top and bottom of the box. From the forward edge of this floor 22, a plate 23 is curved around to extend in an inclined plane rearwardly and upwardly to have a forwardly turned flange 24 fixed to the under side of the top of the damper box 21.

From the rear or outer edge of the floor 22, a plate 25 is curved around to extend in an inclined plane forwardly and downwardly to have its lower forward edge in contact with and welded to the bottom of the damper box 21. In each of the plates 23 and 25 is cut a rectangular opening substantially over the entire area leaving only a bearing surface around the opening for the dampers or doors 26 and 27 to rest thereon as closures for the openings.

The door 27 has its upper end rolled to hold therein the hinge rod 28 preferably made of brass or bronze to prevent corroding, and the hinge plates 29, 30, 31 are notched into the rolled edge to receive there-through the rod 28. The plates 29, 30, 31 are removably bolted to the floor 22, Figs. 2 and 7, to carry the hinge side of the door up within the angular space forwardly of the juncture of the plate 25 with the floor 22 so as to permit the door 27 to be swung upwardly against the underside of the floor 22. The hinge of the door 27 is thus concealed and protected from dust and moisture that may be carried by the air coming through the box 11 toward the door 27.

Similarly the door 26 is hinged removably to the upper side of the box 21 with the hinge concealed and covered from the rear or outer side within the angular space immediately forward of plate 23 at its juncture with the box 21. Both doors 26 and 27 being hinged by their upper ends and inclining downwardly and inwardly may be lifted by air traveling thereagainst from outside the wall 10 to permit the air to pass through the openings in the plates 23 and 25 to overcome a partial vacuum that may be produced on the inside of the wall 10.

A radiator 33 is hung on the inside of the wall 10 by the brackets 34 and 35, Fig. 1,

to have two sections at each end thereof project longitudinally past the box 20. The lower end of the radiator 33 is positioned to have the box section 19 extend thereunder and up along the outer sides of that part of the radiator therein, the sides terminating substantially on vertical lines centrally of the radiator above the section interconnecting nipples, with a semi-circular cut out 54 closely fitting around the back sides of the nipples, and the sides being cut off diagonally rearwardly thereunder, Figs. 3 and 6, back to the lower front edge of the section 19. The upper forward edge of the section 19 extending between the sides thereof terminates substantially against the back sides of the sections of the radiator 33 and has an upturned flange 55 extending to the same level as the two side edges. A front base section 36 is formed with a front wall curved downwardly and rearwardly to extend backwardly and about by its rear edge to abut the forward bottom edge of the floor of the section 19. The section 36 also has two sides extending rearwardly to abut the front edges of the respective sides of the section 19, with semi-circular cut outs 37 around the radiator section coupling nipples, the top edges of the side walls and front wall of the section 36 being in the same plane as that of the rear section side walls and flange 35.

The front section 36 is secured to the rear section by means of the screws 38 passing through each side and screw-threadedly engaging in the arm 39 projecting forwardly from the section 19 on each side, Figs. 2 and 6.

It is thus to be seen that the lower part of the radiator 33 is completely enclosed by the box 20 to the end that only air coming past the dampers 26 and 27 may pass up through the radiator 33. The box 20 is supported from the radiator 33 at each end by a U-bolt 40 encircling the radiator nipple 41 from above and passing by its ends down through the eyes 42, 43 fixed on the sides of the sections 19 and 36 respectively, Fig. 3.

A housing 44 open at the top and bottom and comprised of front and rear halves slidably fitted together vertically on their sides, is carried in a slotted strip 46 around the top edge of the box 20, and completely surrounds that group of radiator sections projecting from the box 20 for substantially the entire height of the sections. A thermostat 56, the detailed construction of which is well known to those versed in the art and is therefore not here shown in detail is mounted on the back side of the housing 44 and has a chain 47 suspended from its movable unit 48, Fig. 2, with a spring 49 therebetween.

The chain 47 passes down around the front side of the pulley 49 mounted on the top of the section 19, and through into the section

19 to engage the arm 50 fixed to the damper 26. A length of chain 51 is fixed to the arm 50 above and to the arm 52 below on the damper 27 and is of such length that when the chain 47 lifts the damper 26 the damper 27 will also be lifted and when the damper 26 closes, the damper 27 closes simultaneously.

The section 19 has a part of its floor cut out rectangularly back from its front edge, and a door 53 is hinged by its back edge to swing forwardly and upwardly to close that opening, the front edge of the door lapping over onto the bottom of the box section 36.

15 A cotter pin 54 is passed through the door, Figs. 2 and 6, to have its looped end or eye thereabove and a spring 55 is engaged in the eye and to a chain 56 extending from the spring up to the arm 50. In some States, laws 20 relating to ventilation of schools and the like prohibit the recirculation of air within a room, in which case, the door 53 is held closed against the bottom of the box 20 by the buttons 57, Figs. 2 and 8. Normally, the 25 door 53 is open as indicated in Fig. 2.

In describing the operation of the invention, it will be assumed first that the air from the room on the inside of the wall 10 is not being exhausted as would be the case during 30 the night. The pressure within the room is then practically the same as that outside the wall 10 so that the pressure is equal on both the outer and inner sides of the dampers 26 and 27 and they therefore normally tend 35 to remain closed, with the bottom door 53 open. Heat from the radiator 33 will cause a flow of air in through the door passageway 53 and up through the radiator housing 44 and out into the room so that the room 40 may be heated by circulation of air entirely therewithin. Now should the temperature of the room rise above that desired, the thermostat 56 will operate to pull the chain 47 so as to lift and open the dampers 26 and 27 45 and close the door 53 to let outside air enter through the box 20 and pass up over the radiator 33 through the housing 44.

Assuming that the room temperature is at or below that desired and that the air is started to being exhausted from the room, a partial vacuum is produced that causes the dampers 26 and 27 to open due to the higher pressure from without so that upon maintaining a constant withdrawal of air from the 55 room, the dampers 26 and 27 automatically open and remain open as long as the vacuum is maintained.

When the dampers 26 and 27 open, the door 53 is moved toward its closing position. 60 The vacuum in the room will cause only a partial opening of the dampers, and as the heat comes in the radiators and the room temperature rises sufficiently, the thermostat 56 may operate to open the dampers 26 and 65 27 further.

In other words, upon exhaustion of air from the room, there is an automatic small opening of the dampers entirely independent of a thermostat or other mechanical means, and operation of the dampers between that 70 small opening and the full opening, is effected by thermostat means as affected by room temperatures. The dampers are not opened against the outside pressure but with and by means of it. By providing two dampers 26 75 and 27 in place of a single damper which may in some cases be desirable, the combined effective openings along the front edges of the dampers is twice that secured from a single damper for the same lift. Also by 80 placing a plurality of dampers across the opening to the housing of the radiator, an effective baffle is introduced that will tend to prevent sudden gusts of wind from unduly surging through the opening. 85

While I have here shown and described my invention in the best form as now known to me, it is obvious that many structural changes may be made therefrom without departing from the spirit of the invention, and I therefore do not desire to be limited to that precise form, nor any more than may be required by the following claims. 90

I claim:

1. In a combined radiator box base and wall box, an outer box, a damper box, an extension sleeve telescopically interconnecting said two boxes, a damper hingedly supported by its upper end in said damper box to slope downwardly and away from said outer box normally closing by gravity a passage through the damper box, said damper being automatically partially opened upon a decrease in pressure on its side away from said outer box, and means for actuating said damper between said partial opening and a full opening thereof. 95

2. The combination with a radiator of an air conducting box having a passageway discharging toward and around the lower part of said radiator, and a door hinged in said box from its top side to drop normally by gravity and rest in an inclined position downwardly therefrom toward said radiator to close said passageway, said door automatically opening upon existence of a lower pressure on the radiator side of the door than on the opposite side. 110

3. The combination with a radiator of an air conducting box having a passageway discharging toward and around the lower part of said radiator, and a door hinged in said box from its top side to drop normally by gravity and rest in an inclined position downwardly therefrom toward said radiator to close said passageway, said door automatically opening upon existence of a lower pressure on the radiator side of the door than on the opposite side, and thermostat means operatively connected with and moving said door 125 130

upon predetermined temperature changes about said radiator, said means moving said door beyond the opening caused by said difference in pressure.

5. 4. The combination with a radiator of an air conducting box having a passageway discharging toward and around the lower part of said radiator, and a door hinged in said box from its top side to drop normally by 70
10 gravity and rest in an inclined position downwardly therefrom toward said radiator to close said passageway, said door automatically opening upon existence of a lower pressure on the radiator side of the door 15 than on the opposite side, and thermostat means operatively connected with and moving said door upon predetermined temperature changes about said radiator, said means moving said door beyond the opening caused 20
25 by said difference in pressure, and said means also actuating said door to and from said closed position in the absence of a difference in pressure on the two sides of the door.

5. In a combined radiator box base and 25 wall damper, a box base surrounding the bottom sides and ends of a radiator having an air inlet and discharging across the radiator, a damper box fixed in the inlet opening of said box and extending into an air intake 30 opening through a wall back of the radiator, a damper hinged in the damper box by its upper edge to drop normally by gravity to close a passage through the damper box, said damper being free to swing toward the radiator to an open position, a thermostat mounted without the damper box, and means interconnecting the thermostat and the damper for pulling the door open upon a predetermined operation of the thermostat. 35

40. 6. In a radiator box base damper, a damper box having a passage to permit air to travel therethrough, a door hinged at its upper edge in the damper box to swing normally by gravity to close said passage, a stop 45 against which the door strikes in its closed position, said stop being on the side of the door in the direction of incoming air, and said stop being located to cause the door to have its upper end sloped angularly toward oncoming air through said box when the door is in a closed position. 50

7. In a radiator box base damper, a damper box having a passage to permit air to travel therethrough, a door hinged in the 55 damper box to swing normally by gravity to close said passage, a stop against which the door strikes in its closed position, said stop being on the side of the door in the direction of incoming air, and a shroud plate about 60 the hinge of said door concealing said hinge on the incoming air side of the door.

8. In a device for admitting air to flow over a radiator, a damper box adjacent the radiator open from both its radiator side and 65 its air intake side, a plate fixed in said box

and having a passageway therethrough, a door on the side of the plate toward said radiator, said door being hinged in relation to said box to drop by gravity from toward said radiator to cover normally said passageway and rest thereover against said plate, the hinged edge of said door being above said passageway out of the path of air passing therethrough. 70

9. In a combined radiator box base and 75 wall damper, a box base removably attached to the wall, a radiator housing removably supported by the box base, a damper box fixed to the base to extend into the wall, a wall box fixed in the wall, a sleeve telescopically surrounding the wall box and the damper box, being removably engaged thereby, and a damper carried within the damper box whereby removal of the box base withdraws the damper from within the wall. 80

10. In a combined radiator box base and wall damper, a box base having a wall flange, a damper box telescopically fitted within the back side of the box base and extending rearwardly from said flange, a flange around the sides, top and bottom of the damper box therewithin, a door having its upper edge rolled to engage around a hinge rod, hinge leaves engaging said rod and removably fixed to the upper side of the damper box on the forward side of said flange to locate the rolled edge of the door closely within the upper angle of the flange with the box whereby the flange on the upper side conceals the door hinge from the rear side and the door may drop by gravity to rest on said flanges and close the opening through the damper box, and means for lifting the door. 90

11. A wall damper box having a passage therethrough, a floor within the passageway, 105 a plate turned rearwardly and upwardly from the front edge of the floor to have its upper end fixed to the top of the box and having an opening therethrough, a second plate turned downwardly and forwardly from the rear edge of the floor and having an opening therethrough, and doors hinged by their top sides to swing normally by gravity from the forward sides of the plates to cover said openings. 110

12. A wall damper box having a passage therethrough, a floor within the passageway, a plate turned rearwardly and upwardly from the front edge of the floor to have its upper end fixed to the top of the box and having an opening therethrough, a second plate turned downwardly and forwardly from the rear edge of the floor and having an opening therethrough, and doors hinged by their top sides to swing normally by gravity from the forward sides of the plates to cover said openings, and hinges supporting said doors, said hinges being above said openings and protected from the rear side by said plates. 115

13. In a device for admitting air to flow over a radiator, a damper box adjacent the radiator open from both its radiator side and its air intake side, a plate fixed in said box and having a passageway therethrough, a door on the side of the plate toward said radiator, said door being hinged in relation to said box to drop by gravity from toward said radiator to cover normally said passageway and rest thereover against said plate, the hinged edge of said door being above said passageway out of the path of air passing therethrough, said plate being angularly disposed across said box to slope away from the radiator.
14. The combination with the wall of a house, of an air conducting box in the wall having a passageway discharging into the house, and a door hinged in said box from its top side to drop normally by gravity and rest in an inclined position downwardly therefrom and inwardly of the house to close said passageway, said door automatically opening upon the existence of a lower pressure on the inside of the house than on the outside.

In testimony whereof I affix my signature.
CLARENCE C. SHIPP.
